UNITED STATES PATENT OFFICE.

CHARLES RYAN, OF GLASGOW, SCOTLAND.

GUIDE FOR BAND-SAWS.

SPECIFICATION forming part of Letters Patent No. 716,763, dated December 23, 1902.

Application filed September 10, 1902. Serial No. 122,766. (No model.)

To all whom it may concern:

Be it known that I, CHARLES RYAN, saw-miller, of St. Rollox Saw Mills, residing at 20 Baird street, Glasgow, Scotland, a subject of the King of Great Britain, have invented a certain new and useful Improved Guide for Band-Saws, of which the following is a specification.

This invention relates to the guides of band-saws; and it has for its object to improve their construction.

The main feature of the invention is the use of a series of balls against which the back of the band works.

15 The guide, which may be otherwise of the usual construction, is made with a groove or guideway or race, in which a series of balls are placed and arranged in such manner that the band as it works bears at its back against 20 the balls or a number of them. If so desired, the guide-race for the balls may be in the form of a flattened ellipse. The guide-race may be undercut, so as to retain the balls in position, and a gateway may be provided at 25 the top for the insertion of the balls. The usual packing-strips may be secured to the guide by means of bent metal clamps and screws.

In order that the invention may be clearly 30 understood, I have hereto appended an explanatory sheet of drawings, whereon—

Figure 1 is a side elevation of the guide. Fig. 2 is a front elevation of the same. Fig. 3 is a cross-section. Fig. 4 shows the guide 35 with its packing-strips removed. Fig. 5 is a plan, and Fig. 6 a front view, of a packing-strip.

a is the guide-supporting bracket of the band-saw machine, b the band-saw, and c the 40 guide.

The guide is made of solid metal with a vertical groove d for the band-saw and a groove e or race of flattened elliptical form for a series of balls f. The groove has a narrow slit 45 or opening at the front, through which the balls can be seen when the packing-strips are removed, as shown at Fig. 4. This slit is sufficiently narrow to prevent the balls falling out of place, and at one side it coincides 50 with and forms a part of the vertical groove d, along which the back of the band-saw works. The band-saw as it moves bears at its back against the balls in the vertical

groove and rubs on them. The balls, which 55 are inserted into the ball-groove by the gate

or opening g at the top of the groove, are made of steel and move freely along the groove under the action of the band-saw.

The wood packing-strips h i are each made, as shown at Figs. 5 and 6, with a ledge j, and the right-hand strip is also made with a part k, which is cut away sufficiently to expose a few of the balls in the ball-groove, as shown at Fig. 2. This exposed part of the ball-groove serves for the escape of sawdust as 65 the balls move around and also for filling in lubricating - oil (or cleansing - oil, paraffin) when necessary. The packing-strips are secured to the guide by the bent clamps l m and thumb-screws n. These screws n pinch 70 against the backing-plate o of the guide.

Having now fully described my invention, what I claim, and desire to secure by Letters Patent, is—

1. The combination of a band-saw guide 75 and a series of balls therein on which the back of the band-saw can work.

2. The combination of a band-saw guide, a groove made in the guide and a series of balls inserted in the groove for the back of 80 the band-saw to work against.

3. The combination of a band-saw guide, an elliptical groove made therein and a series of balls inserted in the groove for the back of 85 the band-saw to work against.

4. The combination of a band-saw guide, a groove made in the guide, a gate for the insertion of balls in the groove and a series of balls inserted in the groove for the back of 90 the band-saw to work against.

5. The combination of a band-saw guide, an elliptical groove made therein, a slit in the face of the groove and a series of balls inserted in the groove for the back of the band-saw to work against. 95

6. The combination of a band-saw guide, a series of balls therein on which the back of the band-saw can work, packing-strips, clamps and screws, substantially as described.

7. The combination of a band-saw guide, 100 a series of balls therein on which the back of the band-saw can work, packing-strips having ledges, a cut-away part on one strip, clamps, and screws, substantially as described.

Signed at Glasgow, Scotland, this 7th day 105 of August, 1902.

CHARLES RYAN.
